UNITED STATES PATENT OFFICE.

RALPH FRANK KNIGHT, OF BEVERLY, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

MACHINE FOR SETTING EYELETS.

1,297,695.

Specification of Letters Patent. Patented Mar. 18, 1919.

Application filed July 7, 1917. Serial No. 179,243.

To all whom it may concern:

Be it known that I, RALPH FRANK KNIGHT, a citizen of the United States, residing at Beverly, in the county of Essex and State of Massachusetts, have invented certain Improvements in Machines for Setting Eyelets, of which the following description, in connection with the accompanying drawings, is a specification, like reference characters on the drawings indicating like parts in the several figures.

This invention relates to improvements in machines for setting eyelets or similar fasteners and is illustrated as embodied in a machine for setting blind or invisible eyelets of the type described in an application of H. W. Kenway, Serial No. 859,632, filed September 1, 1914.

Eyeletting machines of the type referred to are provided with an expandable upsetting die comprising movable sections which are normally held in contracted condition. The upsetting die, in contracted condition, is passed through one or more superposed layers of material into which a blind or invisible eyelet is to be inserted. After the contracted die has passed through the work, it is expanded and the upsetting of the eyelet is effected by forcing the eyelet barrel against the expanded die.

In practice difficulty is experienced in case the expandable upsetting die encounters an eyelet wrongly positioned in the delivery end of the raceway or when the barrel of the eyelet presented to the upsetting die is either distorted or clogged up. Such conditions may cause breakage of the expandable die or interfere otherwise with the proper setting of the eyelets and it is the general object of the invention to obviate such difficulty.

With these conditions in view, an important feature of the present invention consists in a guard for protecting the ends of the sections of an expandable die during its movement relative to the raceway. The guard protecting the ends of the upsetting die sections may be so shaped and dimensioned that it will securely protect the end of the upsetting die sections against encounter with a wrongly positioned or faulty eyelet. As herein shown the guard is constructed so as to clear a passage through a distorted or clogged up barrel of an eyelet.

Another important feature of the inven-

tion consists in die expanding means located within an expandable die. This arrangement is of particular advantage because the die expanding member keeps the interior of the die free from dirt and chips which might prevent proper contraction of the sections of the die. As herein shown, the functions above discussed are taken care of by a single member and this combined guard and die expanding member is also so constructed and arranged that the individual sections of the upsetting die are laterally supported while the die is in expanded condition and that the upsetting flange of the die receives rigid support during the upsetting operation.

These and other features of the invention including certain details of construction and combinations of parts will be described in connection with an illustrated machine shown in the drawings in which—

Figure 1 is a perspective of so much of an eyeletting machine as is necessary to understand the present invention.

Fig. 2 is an exploded view of the setting and expanding tools.

Figs. 3, 4, 5 and 6 are views in side elevation illustrating the successive steps in the cycle of the machine.

Fig. 7 is perspective of the die expanding member.

Fig. 8 is a sectional view on an enlarged scale showing the setting device and the feeding member in position at the conclusion of the setting operation.

The machine frame 2 is provided with vertical journals for a plunger 4 carrying the setting devices. The plunger 4 is reciprocated vertically by a disk cam 6 mounted upon the main shaft of the machine and having a cam track cut into its rear face. The frame 2 also supports a stationary work plate 10 above which operate a punch lever 12 and a feeding lever 14 which will be hereinafter referred to.

The lower setting die 16 is shaped at its upper end to fit the flange of the eyelet to be set and is adjustably mounted in the upper end of the plunger 4, being shouldered to rest upon a hollow bolt 18 threaded into the plunger 4 and provided with a lock nut 20. The setting die 16 is bored to receive the upsetting die member 22 made up of expandable sections and having a setting surface which is formed by the lower surface of an

overhanging shoulder in said sections. The upsetting die illustrated in the drawings comprises eight sections, each of which extends over 45° of its circumference. The body of the upsetting die 22 is hollow to receive the stem 34 of a die expanding member best shown in Fig. 7. The sections of the upsetting die 22 are of resilient nature and are so shaped as to be normally in contact with each other so that the die 22 as a whole is in contracted condition. The upper end of the upsetting die is substantially flat and has a diameter slightly less than the inner diameter of the eyelet to be set. Immediately beneath its upper end the upsetting die 22 is reduced in diameter its surface being curved so as to form a shoulder providing an upsetting surface facing the eyelet carrying set 16. The inner corner of the upper end of each die section is slightly beveled off so that a substantially conical recess is formed at the interior of the upsetting die near its upper end. The upsetting die is arranged to be passed through the hole in the lining part 90 of the upper in its normal or contracted position and in this condition the diameter of the upper end of the upsetting die is slightly less than the diameter of the hole in the work. The body of the upsetting die 16 is threaded into a movable angle piece 26 which is guided for movement in the machine frame and projects in through a slot 28 in the wall of the plunger 4. Beneath the overhanging end of the angle piece 26 is disposed a hollow flanged core 30 between which and the bottom of the plunger 4 is interposed a stiff compression spring 32 tending at all times to elevate the angle piece 26 and the upsetting die 22 carried thereby. The stem 34 of the die expanding member is bent at its lower end and provided with a lateral projection 36 (Fig. 7) which is normally in engagement with the under side of the threaded end of the upsetting die 22. The lower bent end of the stem 34 is spring-tempered so that the die expanding member is resiliently interlocked with the upsetting die when these parts occupy their normal position but may be easily removed when the machine is disassembled. The end and the projection 36 of the stem 34 rest upon the head of a short plunger 38 which bears on the upper end of a compression spring 40 contained within the hollow core 30 and tending to elevate the die expanding member. It will be understood that the eyelet to be set is delivered to the setting die 16 and the clenching operation is effected by the relative movement of the die 16 and the upsetting die 22, which movement compresses the spring 32. The upward movement of the upsetting die 22 is limited by an adjustable stop 68 secured in an oblique groove in a bracket 69 fixed to the frame 2.

The feeding lever 14 carries a feeding member 50 which includes a yielding pin 52 cupped at its lower end for engagement with the die expanding member. The punch lever 12 above referred to is provided with a punch 54 which co-operates with a punching die 56 arranged beneath the punch in a slot in the work plate 10. The punching operation is effected by the downward movement of the punch 54 by swinging the lever 12 by a cam not herein shown. The punching operation takes place at one side of the setting position whereupon the punch is retracted from the work and moved to an inoperative position. The feed lever 14 is subsequently moved so as to carry the feeding pin 52 into alignment with the previously punched hole, then depressed to engage the work and finally moved toward the left while still in engagement with the work to bring the punched hole into alignment with the setting devices. During the insertion of an eyelet the feeding pin 52 is engaged by the rising die expanding member and forced upwardly against the tension of a spring 55 arranged within a casing 60 of the feeding lever 14 permitting the expandable die to rise in closed condition to proper position in the layers of the work as determined by the stop 68 which limits the upward movement of the angle piece 26. A slight downward motion of the lever 14 then causes the feeding pin 52 to force the die expanding member into the expandable die thereby expanding it ready to split and spread the eyelet when the latter is forced upward by the continued upward movement of the plunger 4.

After the contact of the angle piece 26 with the stop 68 the spring 32 is compressed permitting the plunger 4 to continue its upward movement, and as soon as the feeding lever is returned to its initial position, the upsetting die is permitted to contract so that it may be drawn downwardly through the barrel of the clenched eyelet. The movements of the feeding lever 14 are derived from a cam 64 upon the main shaft of the machine. The cam 64 acts upon a roll 65 of a vertical shaft 66 connected with the rear end of the feeding lever 14.

In order to facilitate the entrance of the die expanding member into the barrel of the eyelet, said member is provided with a rounded or conical head 70. The diameter of the base portion of the head 70 is but slightly less than the inner diameter of the barrel of the eyelet, thus enabling the head to clear a passage for the expandable die in case the barrel of the eyelet is either distorted or clogged up. Beneath the base of the head 70 the expanding member is reduced in diameter, thus forming an annular shoulder 72 which is adapted to engage the upsetting flange of the sectional die and give 130

rigid support to said flange during the upsetting operation. By supporting the upsetting flange of the die in this manner the life of the die will be materially prolonged since 5 the strain exerted upon the flange is practically taken up by the annular shoulder 72. Beneath the shoulder 72 the die expanding member is provided with a cylindrical portion 74 of substantially the same length as 10 the barrel of the eyelet to be upset. The cylindrical portion 74 supports rigidly the sections of the die, thus preventing lateral distortion of the die sections during its expansion. The cylindrical portion 74 tapers at 15 76 into the stem 34 to insure a gradual expansion of the die when the die expanding member is forced into the die. It will be noted that the stem 34 is reduced in diameter at its upper end below the tapered portion 70 to permit the complete contraction 20 of the die sections.

The position which the operative parts of the machine assume at the beginning of a cycle is illustrated in Fig. 3. Upon starting 25 the machine the punch 54 descends and perforates the work resting upon the table 10. The raceway 24 is advanced in the usual manner to bring the lowermost eyelet in alignment with the upsetting die 22 as shown 30 in Fig. 4. The punch is then retracted from the work and moved to an inoperative position. The feeding lever is subsequently moved so as to carry the feeding pin 52 in alignment with the previously punched hole, 35 then depressed and finally moved to the left to bring the punched hole into alignment with the setting devices. During these movements of the feeding lever the plunger 4 is elevated and the upsetting die 22 together with the die expanding member enter 40 the barrel of the lowermost eyelet in the raceway 24. The die expanding member constituting a guard for the upsetting die prevents direct engagement of the eyelet and 45 the die. In case the eyelet is wrongly positioned in the raceway the conical head 70 of the die expanding member will deflect the eyelet out of the path of the upsetting die 22. Should the barrel of the eyelet be dis- 50 torted or clogged up the die expanding member is able to clear a passage for the upsetting die and, being resiliently supported on the spring 40, will give slightly before expanding the die sections and assist in preventing breakage of the die. After the upsetting die has entered the barrel of the eyelet 55 the raceway is retracted and the upsetting die enters the previously punched hole of the work by reason of the continued upward movement of the plunger 4. During 60 this movement of the upsetting die the feeding lever 14 is slowly retracted from the work and the die expanding member following the movement of the feeding pin 52 with somewhat greater speed forces the feeding

pin 52 gradually into the member 50 thereby compressing the spring 55. The tension of the spring 55 is less than the tension of the spring 40 in order to prevent under all circumstances expansion of the upsetting die 70 before the latter has passed through the hole of lining part 90 of the work. After the spring 55 is fully compressed the feeding lever is again lowered and the cupped end of the feeding pin 52 forces the die expanding 75 member into the upsetting die thereby separating its sections. When the upsetting die is fully expanded the upsetting flange of the die sections is in engagement with the annular shoulder 72. The cylindrical portion 74 80 gives lateral support to the expanded die sections. During the upsetting operation the upsetting die remains stationary and the barrel of the eyelet is upset by the movement of the eyelet carrying set 16 relatively 85 to the die. The position occupied by the parts at the conclusion of the upsetting operation is illustrated in Fig. 8. The parts are then returned to the position of Fig. 3 ready 90 to repeat the cycle.

Having thus described my invention, what I claim as new and desire to secure by Letters Patent of the United States is:—

1. In an eyeleting machine an expandable upsetting die comprising a plurality of relatively movable resilient sections constructed and arranged to be maintained normally in contracted condition irrespective of the action of gravity and means within the upsetting die for positively separating the sections. 95

2. In an eyeleting machine an expandable upsetting die comprising a plurality of resilient sections maintained normally in contracted condition by the resilience of the sections, and a die expanding member carried by the upsetting die and movable within the die. 105

3. In an eyeleting machine an expandable upsetting die comprising a plurality of resilient sections constructed and arranged to be maintained normally in contracted condition, a member having a die expanding portion carried by the upsetting die, and means to hold the die expanding portion of the said member out of the interior of the upsetting die. 110

4. In an eyeleting machine an expandable upsetting die comprising a plurality of resilient sections constructed and arranged to be maintained normally in contracted condition, a die expanding member carried by the upsetting die and extending through the body of the die, and yielding means to hold the die expanding member in a predetermined inoperative position. 120

5. In an eyeleting machine an expandable upsetting die, comprising a plurality of resilient sections constructed and arranged to be maintained normally in contracted con- 130

- dition, a die expanding member carried by the die and movable within the latter, and means to force the die expanding portion of said member into the contracted portion of said die.
6. In an eyeleting machine an expansible upsetting die comprising a plurality of movable sections constructed and arranged to be maintained normally in contracted condition, a die expanding member carried by the die, means to force the die expanding member into the contracted die, and means to move the die expanding member out of the expanded upsetting die.
- 10 7. In an eyeleting machine an expansible upsetting die, a die expanding member carried by the die, yielding means to hold the expanding member in inoperative position, and means for moving the expanding member positively to expand the die.
- 15 8. In an eyeleting machine, an expansible die having an upsetting flange and a die expanding member carried by the die comprising a stem extending throughout the die, and a head extending normally beyond the upsetting flange of the die.
- 20 9. In an eyeleting machine an expansible upsetting die comprising a plurality of resilient sections constructed and arranged to be maintained normally in contracted condition, and a die expanding member constituting a guard for the expansible die during the passage of the latter through the barrel of the eyelet.
- 25 35 10. In an eyeleting machine, an expansible upsetting die, comprising a plurality of resilient sections forming an upsetting flange maintained normally in contracted condition, and die expanding means carried by the die arranged to pass through the barrel of the eyelet to be set in advance of the upsetting flange of the die to prevent encounter of the upsetting end of the die with the eyelet prior to the expansion of the die.
- 40 45 11. In an eyeleting machine, an expansible upsetting die comprising a plurality of movable sections, a raceway presenting an eyelet to the upsetting die, and a die expanding member carried by the die and held normally above the upsetting flange of the die.
- 50 55 12. In an eyeleting machine, an expansible upsetting die, a die expanding member comprising a stem extending through the die and a head projecting normally beyond the upsetting flange of the die, means to force said member into the die, and means to return the expanding member to inoperative position at the conclusion of the upsetting operation.
- 60 65 13. In an eyeleting machine, an expansible upsetting die, and a die expanding member comprising a stem extending through the upsetting die and an expanding portion adjacent to the upsetting flange of the die constructed and arranged to pass through the barrel of an eyelet to be set in advance of the upsetting die.
- 70 14. In an eyeleting machine, an expansible upsetting die, and a die expanding member comprising a stem extending through the die and a head normally above the upsetting flange of the die, said head being of dimensions to pass through the barrel of the eyelet and constituting a guard for the upsetting die.
- 75 15. In an eyeleting machine an upsetting die comprising expansible sections, and a guard for protecting the ends of the sections during the movement of the die.
- 80 16. In an eyeleting machine an expansible upsetting die comprising a plurality of resilient sections constructed and arranged to be maintained normally in contracted condition, and a die expanding member carried by the die having a head arranged to enter the eyelet to be set in advance of the die, the diameter of said head being greater than the diameter of the contracted die to clear a passage for the die through the barrel of the eyelet.
- 85 90 17. In an eyeleting machine an expansible upsetting die comprising a plurality of resilient sections constructed and arranged to be maintained normally in contracted condition and a die expanding member carried by the die, said expanding member consisting of a stem extending through the upsetting die, and a head tapering toward said stem.
- 95 100 18. In an eyeleting machine an expansible upsetting die comprising a plurality of resilient sections, and a die expanding member carried by the die constructed to support laterally for a distance corresponding substantially to the length of the unclenched barrel of the eyelet the sections of the expanded die.
- 105 110 19. In an eyeleting machine, an expansible upsetting die comprising a plurality of resilient sections, and a die expanding member carried by the die consisting of a stem and a head, the lower portion of said head being tapered to facilitate entrance of the head into the die to expand the die, and a cylindrical portion above the conical end of the head supporting laterally the sections of the expansible die during the upsetting operation.
- 115 120 20. In an eyeleting machine an expansible upsetting die, comprising a plurality of movable sections, and a die expanding member carried by the die, said die expanding member comprising a head having an annular shoulder engaging the upsetting flange of the die and rigidly supporting the latter during the upsetting operation.
- 125 21. In an eyeleting machine an expansible die having an upsetting flange comprising a plurality of movable sections and a die expanding member carried by the die,

- 5 said die expanding member being constructed and arranged to engage the upsetting flange of the die and rigidly support the flange during the upsetting operation.
- 5 22. In an eyeleting machine an expansible upsetting die, a die expanding member carried by the die, and a work feeding member arranged to force the die expanding member into position to expand the upsetting die.
- 10 23. An eyeleting machine comprising an expansible upsetting die, a die expanding member carried by the die, means for holding the die expanding member yieldingly in inoperative position and a work feeding member arranged to move the die expanding member into the die.
- 15 24. In an eyeleting machine, an expansible upsetting die, and a die expanding member carried by the die, comprising a head normally above the upsetting flange of the die and a stem extending through the die, and means to limit the movement of the die expanding member toward inoperative position.
- 20 25. In an eyeleting machine an expansible upsetting die and a die expanding member carried by the upsetting die, the said expanding member comprising a head and a stem, the lower end of which is tempered, and a lateral projection on the lower end of the said stem to limit movement of the die expanding member with relation to the die.
- 25 26. In an eyeleting machine an upsetting die comprising expansible sections, and a die expanding member passing through said die and provided with a resilient portion adapted to engage the die and prevent unintentional withdrawal of the member from the die.
- 30 27. In an eyeleting machine an upsetting die comprising expansible sections and a guard carried by the die for protecting the ends of the die sections during the movement of the die.
- 35 28. In an eyeleting machine an upsetting die comprising expansible sections and a combined guard and die expanding member constructed and arranged to support the expanded sections of the die.
- 40 29. In an eyeleting machine an expansible upsetting die comprising a plurality of sections maintained normally in contracted condition, a die expanding member carried by the die, operating means for the expanding member arranged to force said member into the die, means for urging the operating means yieldingly toward the expanding member and yielding means of greater resistance than the last mentioned means to hold the expanding member out of the die for the purpose of preventing premature expansion of the die.
- 45 30. In an eyeleting machine an expansible upsetting die, a die expanding member, a spring holding the expanding member normally out of the die, and operating means for the expanding member urged toward the expanding member by a spring of less tension than the spring which tends to move the expanding member out of the die.
- 50 31. In an eyeleting machine, an expansible upsetting die comprising a plurality of resilient sections constructed and arranged to be maintained normally in contracted condition, a die expanding member carried by the upsetting die and extending through the body of the die, yielding means to move said member to die expanding position, and other yielding means to move the die expanding member to a position allowing the contraction of the die.
- 55 32. In an eyeleting machine, an expansible die having an upsetting flange and a die expanding member carried by the die comprising a stem extending throughout the die, and a head overhanging the flange of the expansible die when the die is in contracted relation.
- 60 33. In an eyeleting machine, an upsetting die provided with expansible sections, and a guard with a rounded end associated with the exposed end of the die, said end of the guard being shaped to facilitate insertion of the guard and die through the hole.
- 65 34. In an eyeleting machine, an expansible upsetting die, a die expanding member carried by the die, and cam operated means constructed and arranged to force the die expanding member into position to expand the upsetting die.
- 70 35. In an eyeleting machine, an expansible upsetting die, a die expanding member carried by the die and arranged to be presented with the die upon one side of the work, and a member positioned for presentation on the opposite side of the work constructed and arranged to force the die expanding member into position to expand the upsetting die.
- 75 36. In an eyeleting machine, an expansible upsetting die comprising a plurality of sections maintained normally in contracted condition, a die expanding member carried by the die, yielding means constructed and arranged to move the die expanding member to expanding position, and other yielding means of different strength from that of the last mentioned means constructed and arranged to move the die expanding member to an inoperative position to allow the contraction of the die.
- 80 37. In testimony whereof I have signed my name to this specification.

RALPH FRANK KNIGHT.
